UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed July 22, 1922. Serial No. 576,682.

The present invention relates to typewriting machines in which the platen-frame is shiftable between case-positions. More particularly, the invention relates to mechanism 5 for arresting, in middle-case-position, a platen-frame which is shiftable from lower-case-position to either of two other case-positions; to mechanism for locking the platen-frame in lower-case-position against 10 rebound or accidental displacement; and to improved means for locking the platen-frame in middle or upper case positions.

In a machine in which the platen is shiftable from lower-case-position to either a 15 middle or an upper case-position, the stop for determining the middle-case-position must, obviously, not interfere with movement of the platen to upper-case-position; and so is ordinarily itself shiftable between 20 an ineffective and an effective position. This shift of the stop has heretofore been effected by connections from the upper-case-shift-key; the stop being moved by the upper-case-shift-lever to ineffective position to 25 clear the way for the platen-frame when movement of the latter to upper-case-position is desired.

A feature of the present invention is to 30 relieve the upper-case-shift-key of the burden of such stop-operating connections by the provision of a stop which is normally in ineffective position and only becomes effective when the middle-case-shift-key is operated.

35 In typewriting machines in which the platen-frame is shiftable between case-positions, it is desirable to prevent rebound of the platen-frame after a case-shifting operation, so that the typing alignment will not 40 be disturbed. More particularly in machines of the so-called portable class, it is also desirable to have provision for locking the platen-frame against shifting movements in the casing in which it is carried.

45 Another feature of the present invention is the provision of a lock, for the above purposes, which is effective at all times except when a shift-key is operated; and which, where the machine provides for three case-positions of the platen-frame, may be thrown to ineffective position by either the middle or the upper case shift-key, whenever either of the shift-keys is operated. A 50 feature of the invention is the provision of

means for automatically returning the lock 55 to effective position upon release of the shift-key which has previously disabled the same.

A further feature of the invention resides in providing the shift-key levers for 60 moving the platen-carriage to middle and upper case positions, with improved locking devices singular to each shift-lever. Each locking device in this instance includes a lock-arm pivotally mounted on the shift-lever at an intermediate point thereof, having an auxiliary operating or locking key, 65 preferably located to the rear of the shift-lever operating key, and a latch or lock within the frame capable of maintaining 70 the platen-carriage in the shifted case-position. The auxiliary key is depressible by a finger-stroke practically unidirectional 75 with that ordinarily required for the shift-key or writing keys, to operate the latch, and the latch is automatically returnable to its normal ineffective position by a slight subsequent depression of the shift-key.

Other features and advantages will hereinafter appear.

In the accompanying drawings, which illustrate a machine of the portable type disclosed in Campbell Patents Nos. 1,332,972 and 1,433,935.

Figure 1 is a side view, partly cross-sectional, of a typewriting machine embodying 85 the invention.

Figure 2 is a view similar to Figure 1, except that the parts are in middle-case-position.

Figure 3 is a view similar to Figures 1 and 2, with the parts in upper-case-position.

Figure 4 is a top plan view, certain of the parts being broken away for clearer illustration of other parts.

The machine herein illustrated is of the front-strike class; one of the type-bars 10, carrying types 11, 12 and 13, being shown in printing position against the platen. 100 The normal or lower-case position of the platen is indicated at 14 in full lines in Figure 1, and the middle and upper case-positions of the platen are indicated in dotted lines, at 15 and 16, respectively. The platen 105 is journaled in a sheet-metal carriage 17, which travels to the left under the control of the escapement-mechanism (not shown),

and which is provided with roller-bearings 18 and 19, by means of which it travels on tracks 20 and 21. The tracks 20 and 21 form part of the shift-frame, which also includes a downwardly-extending member 22 and forwardly-extending members 23; the latter being pivoted, at 24, to links 25, one at each side of the machine. The links 25 are pivoted, at 26, to the main frame 27, 10 nearly behind and somewhat below the normal positions of the pivots 24.

For guiding the shift-frame in its movements between case-positions, there are provided, one at each side of the machine, other links or rock-arms 28, fast on a rock-shaft 29, journaled in the main frame of the machine, and extending transversely from side to side thereof. Each link 28, near its distal end, carries a pin 30, and the corresponding side piece 23 of the shift-frame has a yoke or recess 31 formed therein, to receive the pin 30 when the shift-frame is properly set upon the links 28.

For moving the shift-frame between case-positions, there are provided two levers 32 and 33, fulcrumed on a rod 34, at the rear of the machine, and held in and returned to normal position by springs 35 and 36, respectively. The springs 35 and 36 are secured by a screw 37 to the lower rear cross-piece 38 of the main frame, and at their distal ends 39 and 40, respectively, engage in openings in the shift-levers. The levers 32 and 33 are provided with keys 41 and 42, respectively. Depression of the key 41 effects movement of the shift-frame to middle or capital case-position, and depression of key 42 to upper or figure case-position. The normal position of the levers is determined by a cross-piece 43 in the frame at the front of the machine, above a front piece 71, which latter may be formed as a comb-plate with the key-levers located in corresponding interstices thereof.

For effecting movement of the shift-frame, the lever 32, at an intermediate point thereof, is provided with a laterally-projecting pin 44, adapted, upon depression of the lever, to engage the forward arm 45 of a lever 46, pivoted at 47 to an ear 48, turned up from a bracket 49, on a cross-tie 50 connecting the side plates of the main frame. An arm 51, forming part of the lever 46, extends rearward from the pivot 47 and engages the under side of an arm 52, turned up from an ear 53, which is set into and made fast to the rock-shaft 29. The normal position of the shift-frame is determined by screws 54, which pass through, 60 and are carried by, flanges 55, turned laterally from the side pieces 23 of the shift-frame. The lower ends of these screws, by contact with the cross-piece 50, serve as stops, and the screws thus support the shift-frame on the cross-piece 50 in lower-case-po-

sition of the parts. By means of lock-nuts 56, the screws may be adjusted and set for the proper lower-case-position of the frame, and the frame be evenly supported at both sides. In the position of the shift-frame, 70 as determined by the stop-screws 54, the arm 52 lies in contact with or immediately over the arm 51 of the lever 46. The arms 51 and 52 have their engaging surfaces so shaped that a cam and rolling action of one 75 on the other takes place when the shift-key is depressed. This cam-action causes the point of application of the leverage on the arm 52 to shift as the lever-arm 51 and the shift-frame swing up, thereby compensating 80 for the change in angular position of the parts and rendering the action a light and easy one.

A hook or dog 57, forming a third and upwardly-extending arm of the lever, has a tooth 58 on the upper end thereof, which, in the normal, Figure 1, position of the lever 46, and lower-case-position of the shift-frame, projects over a tooth 59, formed on the end of the arm 52; and thus serves to hold the shift-frame locked down in lower-case-position, as well as the frame 23 and the carriage 17; the three members 28, 23 and 17 being connected in usual practice, as shown in said patents. A spring 60, attached at one end to the arm 51 of the lever 46, and at its other end to a pin 61 set into a member 62, which may be a part of the cross-tie 50, normally holds the lever 46 in such position as to maintain the tooth 58 in effective position over the tooth 59, and serves automatically to cause the hook 57 to lock down the arm 52 when the shift-frame returns to lower-case-position. The arm 51 is shown as having play in a slot 63 in the member 62. The spring 60, by causing the forward arm 45 of the lever 46 to move upward, and by the engagement of the arm 45 with the pin 44, may serve to assist in the return of the shift-lever 32 to normal position. The angular set of the hook or arm 57 is such that, when the key-lever 32 receives its initial downward movement, the tooth 58 on the arm 57 is moved from over the tooth 59 on the arm 52 before the arm 51 of the lever 46 begins to exert its upward pressure on the arm 52. To insure this preliminary disengagement of the teeth 58 and 59, a slight clearance may be provided between the arms 51 and 52 in their normal positions. The hook or lock 57 will prevent undesirable movement and play of the shift-frame when the machine is being transported within its casing.

Throw of the shift-frame beyond middle-case or capital-writing position, upon depression of the key 41, is prevented by means of stop-arms 64, one at each side of the machine and carried by or forming part of a bail comprising a cross-piece 65. The arms 130

64 and bail, of which they form a part, are pivoted, at 66, to the side members of the main frame 27. Each arm 64, at its upper end, has an ear 67, offset laterally therefrom, and each ear 67 has adjustably set therein, by means of a lock-nut 68, a screw 69. As shown in Figure 1, a spring 70, attached at one end of the cross-piece 65 of the bail, and at its other end to the comb-plate or front piece 71 of the main frame, holds the bail in such angular position that the stop-screws 69 are out of the path of ears 72, offset laterally, one from each of the side plates 23 of the shift-frame. With the bail in its Figure 1 position, the shift-frame is free to rise past middle-case-position to upper-case-position. On movement of the bail with the arm 64 to Figure 2 position, however, it will be noted that the stop-screws 69 will be brought into the path of the ears 72, so that, upon arrival of the shift-frame at middle-case-position, it is arrested in such position. This movement of the bail with the arm 64 is desired only when the middle-case-shift-key 41 is depressed; and, for effecting such movement of the bail, the shift-lever 32 has formed thereon a finger 73, carrying a pin 74, movable in an arcuate slot 75 in an ear 76, formed on the bail. In the Figure 1 or lower-case position of the parts, the pin 74 is at the upper end of the slot 75. As the key 41 is depressed, however, the pin 74 traverses the slot 75 until it strikes the wall forming the lower end thereof, whereupon further movement of the lever 32 causes the bail and arm 64 to be rocked around their pivots 66 against the action of the spring 70 until the stop-screws 69 are in the path of the ears 72 on the shift-frame. This movement of the bail, of course, takes place before the movement of the shift-lever 32 has been sufficiently extensive to lift the shift-frame with the ears 72 to Figure 2 position.

45 For locking the shift-frame and shift-lever 32 in middle or capital case-position, there is pivoted at 77 on the lever 32, just inside the frame-piece 71, a lock-lever 78, having a finger-piece 79 on the forward end thereof, and having a dog or detent 80, in this instance forming another arm thereof. A spring 81, attached at one end to the lever 32, and at its other end to the arm 80 of the lock-lever, normally holds the latter in ineffective, Figure 1, position and returns the lock-lever to such position when free to do so. Depression of the lock-lever to Figure 2 position against the action of the spring 81, however, brings a tooth 82 on the lock-lever under a tooth 83 at the rear of the front piece 71 within the main frame, and thereby causes the shift-lever 32 to be held down against the action of its return-spring 35 when the operator removes his finger from the finger-piece 79 of the

lock-lever, upon engagement of the teeth 82 and 83. The pressure of the spring 35 on the shift-lever 32 causes the tooth 82 to remain in frictional engagement with the tooth 83, despite the tension of the spring 81, until such time as pressure may be applied to the key 41. Even where the middle-case-position of the key-lever 32 is determined by a stop, there will be enough spring in the lever and other parts to eliminate the friction between the teeth 82 and 83, so that, upon such pressure, the spring 81 may move the lock-lever 78 to ineffective position, to permit return of the shift-lever 32 when desired. Where the shift-frame is desired to be locked in middle-case-position, the shift-lever 32 may be operated by means of the finger-piece 79 on the lock-lever 78 in a well-known manner, that is to say, by having a tooth 78^a on the lock-lever 78 offset over the top of the shift-lever 32, so that depression of the lock-lever causes the tooth 78^a to engage and depress the shift-lever. As shown in Figure 4, the tooth 83 on the frame front-piece, which is engaged by the lock-lever-tooth 82, is formed at the end of a slot in a small interior horizontally disposed angular bracket or stop plate 82^a, in which the arm 80 of the lock-lever moves to and from effective position. An offset 78^b on the lock-lever 78, by engagement with the under edge of the shift-lever 32, determines the normal or ineffective position of the lock-lever, and prevents overthrow of the same by the return-spring 81 of the latter.

For movement of the shift-frame to upper-case or figure-printing position, the lever 33 is employed. This lever, like the lever 32, has a pin 84, corresponding to the pin 44, projecting laterally over the arm 45 of the lever 46. Depression of the upper-case-key 42, therefore, actuates the lever 46 in exactly the same way as does depression of the key 41, to cause the arm 51 on the lever 46, by engagement with the arm 52 on the shift-frame, to lift the latter, all as shown in Figure 3. If the key 42 is operated when the parts are in Figure 1 position, the movement of the lever 46 first acts to unlock the shift-frame by moving the tooth 58 from above the tooth 59. There is, however, no connection between the lever 33 and the bail which comprises the stop-arms 64. Consequently, when the key 42 is operated, the bail remains in its normal, Figure 1, position, and does not interfere with the movement of the shift-frame beyond middle-case-position to upper-case-position. The upper-case-position of the shift-frame is determined by a pair of stops, one at each side of the machine, consisting of arms 85, fixed to the cross-piece 50, and having ears 86 offset on their upper ends; in which ears screws 87 are adjustably set by means of lock-nuts 88. As indicated

in Figure 3, these screws 87 are in the path of flanges 89, offset from the lower edges of the side pieces 23 of the shift-frame, so that, when the shift-frame reaches its proper upper-case-position, the flanges 89 strike the lower ends of the screws 87, and the shift-frame is arrested.

For locking the shift-frame in upper-case-position, the shift-lever 33 is provided with 10 a lock-lever 90, in construction and in operation similar to the lock-lever 78 on the shift-lever 32.

Variations may be resorted to within the scope of the invention, and portions of the 15 improvements may be used without others.

Having thus described my invention, I claim:

1. In a typewriting machine, a platen, a frame on which the platen is mounted for 20 movement between case-positions, an arm for effecting such movement of the platen-frame, a finger on the arm at right angles to the arm, and a tooth on the finger engageable with the platen-frame to lock the same 25 against movement when the platen-frame is in normal position.

2. In a typewriting machine, a platen, a frame for the platen, movable from a lower case to a middle case and to an upper-case-position, an arm for effecting such movements of the platen-frame, means on the arm for locking the platen-frame in lower-case-position when the arm is in normal position, a middle-case-shift-lever, an upper-case-shift-lever, and means whereby the arm 25 may be operated by either of the shift-levers.

3. In a typewriting machine, a platen, a frame for the platen, movable from a lower case to a middle case and to an upper-case-position, an arm for effecting such movements of the platen-frame, means on the arm for locking the platen-frame in lower-case-position when the arm is in normal position, a middle-case-shift-lever, an upper-case-shift-lever, means whereby the arm may be operated by either of the shift-levers, and means for automatically moving the arm to normal position to lock the platen-frame upon release of the shift-lever which has operated the arm.

4. In a typewriting machine, a platen, a frame for the platen, movable from a lower case to a middle case and to an upper-case-position, a horizontally-disposed lever pivoted at an intermediate point thereof for engaging the platen-frame rearward of such pivot, to move the frame between case-positions, a middle-case-shift-lever and an upper-case-shift-lever, both engageable with the first-mentioned lever forward of the pivot of the first-mentioned lever, and a vertically-disposed finger on the first-mentioned lever, having a tooth thereon for engagement with the platen-frame to lock the latter in lower-case-position.

5. In a typewriting machine, a platen, a frame for the platen, movable from a lower case to a middle case and to an upper-case-position, a horizontally-disposed lever pivoted at an intermediate point thereof, the 70 arm of said lever rearward of its pivot being shaped for a rolling or cam engagement with the platen-frame, a middle-case-shift-lever, an upper-case-shift-lever, and means whereby the arm of the first-mentioned lever, forward of its pivot, is engageable by either of the last-mentioned levers to be operated thereby.

6. In a typewriting machine, a platen, a frame on which the platen is mounted for 80 movement from lower-case-position to a middle-case-position and to an upper-case-position, a pivoted stop-arm movable from an ineffective position to an effective position for arresting the platen-frame in middle-case-position, means on the platen-frame engageable by said stop-arm in middle-case-position, a middle-case-shift-lever, a pin-and-slot connection between the middle-case-shift-lever and the stop-arm for throwing the latter to effective position after a predetermined movement of the middle-case-shift-lever, and for assuring the return of the stop-arm to ineffective position, and an upper-case-shift-lever.

7. In a typewriting machine, a platen, a frame on which the platen is mounted for movement from lower-case-position to a middle-case-position and to an upper-case-position, a pivoted stop-arm movable from an ineffective position to an effective position for arresting the platen-frame in middle-case-position, means on the platen-frame engageable by said stop-arm in middle-case-position, a middle-case-shift-lever, a pin-and-slot connection between the middle-case-shift-lever and the stop-arm for throwing the latter to effective position after a predetermined movement of the middle-case-shift-lever, and for assuring the return of the stop-arm to ineffective position, means for urging the stop-arm to ineffective position upon release of the middle-case-shift-lever, and an upper-case-shift-lever.

8. In a typewriting machine, a platen, a frame on which the platen is mounted for movement from lower-case-position to a middle-case-position and to an upper-case-position, a stop-lever pivoted at an intermediate point thereof movable from an ineffective position to an effective position for arresting the platen-frame in middle-case-position, means on the platen-frame engageable by said stop-lever in middle-case-position, a middle-case-shift-lever, a pin-and-slot connection from the middle-case-shift-lever to the lower arm of the stop-lever to cause the upper arm with the stop thereon to be swung to effective position after a predetermined movement of the middle- 120

case-shift-lever, and to assure the return of the stop to ineffective position, a device acting on to the lower arm of the stop-lever for yieldably urging the same to ineffective position upon release of the middle-case-shift-lever, and an upper-case-shift-lever.

9. In a typewriting machine, in combination, a platen, a carriage therefor, a track frame on which the carriage travels and to which it is held, a swingable lifting frame pivotally connected to said track frame, a pivoted lever having a work-arm to engage and move said lifting frame, a latch to engage said lifting frame and hold it and the platen in lower-case position, and a power arm to operate said lever and release said lifting frame, a middle-case shift-lever to engage said power arm to operate said lever, and an upper-case shift-lever to engage said power arm to operate said lever.

10. In a typewriting machine, in combination, a platen, a carriage therefor, a track frame on which said carriage travels, a main frame in which said track frame is shiftable and comprising a cross-member, stop-members extending upwardly from said cross-member and having portions to overlie portions of the track frame to limit its upward movement, a bracket extending forwardly from said cross-member, a lever pivoted in the forward end of said bracket, and having a rearwardly-extending work-arm to lift the track frame and a forwardly-extending power arm, and middle-case and upper-case shift-levers to operate said lever through its power arm to shift the platen to middle-case and upper-case positions, respectively.

11. In a typewriting machine, in combination, a platen shiftable to different positions to receive typings in different cases, a traveling carriage therefor, a main frame having a front wall with a projection on the rear face thereof, a case-shift lever projecting forwardly beyond said front wall, and a locking lever pivoted on said case-shift lever just to the rear of said front wall and having a forwardly-extending operating arm with stops to engage the upper and lower edges of the case-shift lever to limit the motion of the locking lever with relation to the shift-lever, and a finger projecting upwardly from the locking lever at its pivot adjacent said projection so that depression of the forward end of the locking lever will depress the case-shift lever and cause the upper end of the finger to move beneath said projection to hold the shift-lever depressed.

12. In a typewriting machine, the combination with a platen, a main frame including a front comb, a case-shift frame and a case-shift lever, of a lock-lever pivoted for movement on said case-shift lever, said lock-lever carrying an upstanding finger, and a stop-member comprising an angular plate secured

to one side of the front comb adjacent the upper edge thereof, said finger arranged to engage the under edge of the plate to cause said shift-lever to hold the shift-frame in an upper-case position.

13. In a typewriting machine, the combination with a platen, a main frame including a front comb, a case-shift frame and a case-shift lever, of a lock-lever pivoted for movement on said case-shift lever, said lock-lever carrying an upstanding finger, a stop-member comprising an angular plate secured to one side of the front comb adjacent the upper edge thereof, said finger arranged to engage the under edge of the plate to cause said shift-lever to hold the shift-frame in an upper-case position, and a spring connected to said upstanding finger and to the shift-lever to throw the lock-lever to ineffective position upon pressure on the shift-lever sufficient to eliminate friction between the finger and the under edge of said stop-member.

14. In a typewriting machine, the combination with a platen, a main frame including a front comb, a case-shift frame and a case-shift lever, of a lock-lever pivoted for movement on said case-shift lever, said lock-lever carrying an upstanding finger, and a stop-member comprising an angular plate secured to one side of the front comb adjacent the upper edge thereof, said finger when depressed causing the finger to first bear against the side of the plate and then slide downwardly thereagainst to the lower edge of the plate, the finger then engaging under said lower edge to lock the shift-lever in upper-case position.

15. In a typewriting machine, the combination with a platen, a main frame including a front comb, a case-shift frame and a case-shift lever, of a lock-lever pivoted for movement on said case-shift lever, said lock-lever carrying an upstanding finger, a stop-member comprising an angular plate secured to one side of the front comb adjacent the upper edge thereof, said finger when depressed causing the finger to first bear against the side of the plate and then slide downwardly thereagainst to the lower edge of the plate, the finger then engaging under said lower edge to lock the shift-lever in upper-case position, and a spring connected to said upstanding finger and to the shift-lever to throw the lock-lever to ineffective position upon pressure on the shift-lever sufficient to eliminate friction between the finger and the under edge of said stop-member.

16. In a typewriting machine, a platen, a frame supporting said platen for case-shifting movement, a shift-lever fulcrumed at the rear of the machine, an intermediate member operatively engageable with said platen-frame and said shift-lever, said intermediate member including provision for rolling contact with said platen-frame, and means de-

pendent upon said intermediate member for locking said platen-frame in normal case-position.

17. In a typewriting machine, a platen, a frame supporting said platen for case-shifting movement, a plurality of case-shift levers, each supported at the rear of the machine and having an effective downward movement, and a single intermediate member alternately engageable by both of said case-shift levers, said intermediate member including provision for leverage changing rolling contact with said platen-frame.

18. In a typewriting machine, a platen, a frame supporting said platen for case-shifting movement, and a triple-armed operator for effecting such movement, said operator including a lifting arm engageable with said platen-frame, a power arm and a lock arm normally operative to prevent movement of the platen-frame, said lifting arm being shaped to afford rolling contact with said platen-frame.

19. In a typewriting machine, a platen, a frame supporting said platen for case-shift-

ing movement, and a triple-armed operator for effecting such movement, said operator including a rearwardly-extending lifting arm, a forwardly-extending power arm and an upwardly-extending lock arm, said lock arm being operative to prevent movement of said platen-frame when said lifting arm is inoperative, said lifting arm having rolling contact with said platen-frame.

20. In a typewriting machine, a platen, a frame supporting said platen for movement from lower case to middle case and upper case positions, a middle-case shift-lever, an upper-case shift-lever, both of said shift-levers having a fulcrum at the rear of the machine, an intermediate arm operatively engageable with both of said shift-levers and with said platen-frame, a lock on said intermediate arm normally preventing movement of the platen, a stop movable into operative position by said middle-case shift-lever, and a stop for limiting shifting movement to upper-case position.

ALFRED G. F. KUROWSKI.
